(57) CLAIM

The ornamental design for a cleaning device, as shown and described.

DESCRIPTION

FIG. 1 is a top front perspective view of a cleaning device and an exemplary environment;

FIG. 2 is a top front perspective view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The portions of the cleaning device and environment shown in broken lines are for illustrative purposes only and form no part of the claimed design.

1 Claim, 8 Drawing Sheets

FIG. 2

FIG. 3

FIG. 4

FIG. 5

FIG. 6

FIG. 7

FIG. 8
